SHOE SEWING MACHINE

Fred Ashworth, Wenham, Mass., assignor to
 United Shoe Machinery Corporation, Borough
 of Flemington, N. J., a corporation of New
 Jersey

Application June 4, 1937, Serial No. 146,409

15 Claims. (Cl. 112—47)

The present invention relates to shoe sewing machines, and more particularly to a machine for attaching a welt to an unlasted upper in the manufacture of shoes of the pre-welt type.

5 It has been found that the lasting of the welted upper may be simplified and the appearance of the completed shoe improved if the margin of the upper around the toe portion of the shoe is puckered or gathered slightly during the operation of 10 sewing the upper and welt together. The puckering operation results in partially shaping the upper before the welt is attached, thereby reducing the effort required to secure the proper return of the margin of the upper over the last, such shaping 15 being particularly difficult in the case of pre-welt shoes because of the stiffness imparted to the upper by the attached welt.

The present invention has for its object the provision of a shoe sewing machine for sewing a 20 welt to the margin of an unlasted upper, having novel and improved mechanism for puckering the upper during the sewing operation, whereby the upper is secured to the welt with the margin of the upper in puckered condition.

25 To this end, a feature of the invention contemplates the provision in a shoe sewing machine having stitch forming, work feeding, and work clamping devices adapted to sew a welt to the margin of an unlasted upper, of means actuated 30 during the time the work is clamped to feed the upper with relation to the welt to pucker the upper and cause the welt and upper to be secured together with the margin of the upper in puckered condition.

35 Another feature of the invention resides in the provision of upper puckering mechanism which may be readily adjusted by the operator during the sewing operation whereby the amount of puckering imparted to the upper may be varied 40 from the maximum to zero.

More specifically, another feature of the invention contemplates utilizing the movements of the work clamping devices to move the feed member or point of the upper puckering mechanism into 45 and out of engagement with the upper, and actuating said feed member or point independently of the movement of said work clamping devices to pucker the upper. By utilizing the movements of the work clamping devices to impart work engaging and disengaging movements to the feed point, and by causing the puckering movements to be imparted to the feed point in proper timed 50 relation to the movements of the work clamping devices, the feed point may be given any suitable 55 quadrilateral motion with relatively simple mech-

anism. In addition, such an arrangement permits the magnitude of the puckering stroke of the feed point to be adjusted independently of the movement of the work clamping devices.

5 Other objects and features of the present invention will be apparent to those skilled in the art from the following description taken in connection with the accompanying drawings, in which Fig. 1 is a view in left side elevation of a shoe sewing machine embodying the invention, indicating certain of the enclosed operated parts in broken lines; Fig. 2 is a view in front elevation, on a somewhat larger scale, of the machine illustrated in Fig. 1; Fig. 3 is a detail sectional view showing the cam shaft, rock shafts, and actuating means therefor, taken on the line 3—3 of Fig. 1; Fig. 4 is a detail view in front elevation, on an enlarged scale, of the parts adjacent the sewing point, showing the puckering device, presser-foot, work support, needle and awl, and with portions of a welt and upper being operated upon; Figs. 5 and 6 are fragmentary views of the parts illustrated in Fig. 4, taken at different times in the cycle of operation of the machine; Fig. 7 is a top plan view, partly in section, of the parts illustrated in Fig. 4; Fig. 8 is a detail view in left side elevation, partly in section, taken along the line 8—8 of Fig. 4, but with the mechanism in the position represented by Fig. 5; Fig. 9 is a 10 right hand sectional detail of the welt guide and feed point, taken along the line 9—9 of Fig. 4; Fig. 10 is a top plan detail view of the presser foot, edge gauge, needle and feed point, taken along the line 10—10 of Fig. 4; Fig. 11 is a detail view of the adjusting arm of the feed point actuating mechanism; Fig. 12 is a detail view in front elevation, partly in section, of the puckering device and certain of its actuating means, taken along the line 12—12 of Fig. 7; and Fig. 13 is a detail 15 sectional view of the same taken along the line 13—13 of Fig. 12.

The shoe sewing machine illustrated in Figs. 1 and 2 as embodying the invention is a straight hook needle, chain stitch sewing machine of the type generally known as the "Puritan" machine, certain features of which are specifically described in U. S. Letters Patent to Frank W. Merrick Nos. 490,854, issued January 31, 1893, 490,856, issued January 31, 1893, and 629,108, issued July 18, 1899.

45 The machine is provided with stitch forming and work feeding devices comprising a straight hook needle 2, a straight awl 4, a needle threading looper 6, and a needle cast-off 8. These devices are actuated from a sewing cam shaft 10 jour-

nailed in bearings in the head portion 12 of the frame of the machine.

The cam shaft 18 is rotated by means of a belt 14 driven by a motor, not shown, in the base of the bench or pedestal 16 upon which the machine is mounted, the belt running over a pulley 18 comprising the continuously rotating portion of clutch mechanism for starting and stopping the machine, while the member 20 is secured to the cam shaft 18, and constitutes the cooperating clutch member. A lever 22 pivotally mounted on the machine frame is provided with an arm adapted to bear against a pin 24 in the center of the member 18, the other arm of the lever 22 being connected to a foot treadle, not shown, which may be actuated by the operator to engage the clutch and start the machine. The machine is stopped by releasing the treadle, a spring 26 rocking the lever 22 to disengage the clutch and also 20 to apply a friction brake 28 by which the cam shaft is brought quickly to rest.

The needle is secured in the end of a needle bar 30 mounted to permit vertical sliding movement in an arm 32. The needle cast-off 8 is likewise secured to a cast-off bar 34 slidably mounted in the arm 32 parallel to the needle bar 30.

The needle is reciprocated vertically by connections from the cam shaft 18 comprising an eccentric 36 on the cam shaft, an eccentric strap 38 surrounding the eccentric, a rod 40 connecting the eccentric strap with an arm on rock shaft 42 in the base portion 44 of the machine frame, an arm 46 on the other end of the rock shaft, and a link 48 between said arm and the needle bar 30. 35 The cast-off 8 is actuated by similar connections, enumerated as follows: An eccentric 50 on the cam shaft 18, an eccentric strap 52, a rod 54 connecting the eccentric strap with an arm on one end of a rock shaft 56 in the base 44, an arm 58 on the other end of the rock shaft, and a link 60 joining the arm 58 with the cast-off bar 34.

The arm 32 in which the needle and cast-off bars are mounted is arranged for rocking movement to cause the needle to feed the work past the sewing point. The arm is secured to a rock shaft 62 pivotally mounted on conical pointed screws 64 in the base of the machine and is rocked by connections from the cam shaft 18 in a forwardly or work advancing direction when 45 the needle is through the work, and in a backward or retracting direction when the needle is withdrawn from the work. These connections comprise a yoke 66 embracing the eccentric 36, and a work feeding lever 70 secured at its lower end to an arm 72 on the rock shaft 62. By mechanism indicated generally at 74 and comprising a series of pivotally connected yokes arranged as described in Letters Patent No. 490,854 above referred to, the center about which the lever 70 is rocked by eccentric 36 may be raised or lowered by handle 76, with the result that the arc 50 of rock of the work feeding arm 32 may be adjusted to produce any desired rate of feed.

The awl 4 is clamped in the lower end of an awl bar 78 mounted for vertical sliding movement in the head portion 12 of the machine frame, the awl bar being reciprocated by means of a crank disc 80 on the end of the cam shaft 18 and a connecting rod 82 which links the crank pin with a pivot block 84 on the awl bar 78.

The thread is placed in the hook of the needle when the needle is through the work by means of a looper 6 actuated by mechanism described in Patent No. 490,856 heretofore mentioned, by which the looper is caused to travel in

a substantially circular path around the needle. The looper 6 is mounted in the downwardly extending arm of a sleeve 86 pivotally secured to the lower end of an eccentric strap 88 surrounding a spherical surface eccentric 90 on the cam shaft 18. The sleeve is also rotatably mounted on a rod 92 pivoted at one end for vertical rocking movement on center screws 94 in the machine frame. The thread on its passage to the looper is drawn through a wax pot 95 of conventional arrangement mounted on the head of the machine.

The machine is provided with means for supporting the work adjacent the sewing point comprising a work support 96 clamped in the upper end of an arm 98 pivotally mounted on the base portion of the machine frame. The work support is provided with an elongated aperture 100 through which the needle passes, and an edge gage 102 is adjustably secured to the support for 20 guiding the work. The arm 98 is locked in vertical position by means of a pin 104 which may be slid by handle 106 lengthwise through lugs 108 on the base of the machine into and out of engagement with the lug 110 on the arm 98. 25 With the pin out of lug 110, the arm may be swung to one side to expose the needle and cast-off.

The work is clamped intermittently against the work support 96 between each work feeding 30 movement of the needle by means of a presser foot 112 on the lower end of a presser foot bar 114. The presser foot bar is mounted in the head portion of the machine parallel to the awl bar 78, and is raised and lowered in proper timed 35 relation to the stitch forming devices by mechanism more fully illustrated and described in Letters Patent No. 629,108, above referred to, the presser foot bar being urged downwardly to clamp the work by a spring 116 mounted on 40 the head of the machine and bearing against the end of the presser foot bar 114.

The presser foot actuating mechanism comprises an eccentric 118 on the cam shaft, an eccentric strap 120 surrounding the eccentric 45 and pivotally connected to an arm 122 secured to one end of a rock shaft 124 comprising a sleeve surrounding and relatively rotatable with respect to an inner rock shaft 126 pivotally mounted on lugs 128 projecting from the head of 50 the machine. The inner rock shaft 126 forms a portion of the actuating mechanism, hereinafter described, for puckering the upper. The other end of the outer rock shaft 124 is provided with an arm 130 which extends into an aperture in 55 one arm of a lever 132 pivotally mounted on the inner rock shaft 126, the arm 130 being engaged by set screws 134 by which the angular position of the lever 132 with respect to the rock shaft 124 may be adjusted.

The presser foot is raised during counter-clockwise rocking movement of the lever 132, as viewed in Fig. 2, by the engagement of the arm 130 with a lug on block 138 which actuates clutching mechanism to lock said block to the presser 65 foot bar 114, whereby continued counter-clockwise movement of the lever 132 lifts the presser foot to unclamp the work. The clutching mechanism comprises a cylindrical nut 140 threaded to engage a rapid pitch screw thread 142 formed in the upper end of the presser foot bar 114. The nut 140 fits loosely inside a cylindrical bore in block 138, and is free to rotate therein except when the block is tilted by lever 132, jamming the nut against rotation and thus preventing move- 70 75

ment of the block with relation to the presser foot bar.

Adjustment is provided for the amount the presser foot is raised above the work by means of a sleeve 144 surrounding the upper portion of the presser foot bar and adapted for independent vertical sliding movement in the head of the machine. The sleeve has at its lower end an offset portion within which the block 138 and nut 140 are received. A flat spring 146 bears against the upper end of the sleeve to insure its return to lowered position as the presser foot descends to work clamping position. The downward movement of the sleeve is limited by nuts 148 at the top of the sleeve, which may be adjusted to vary the point to which the sleeve descends. Since the point in the rocking movement of the lever 132 at which the clutching mechanism engages and releases the presser foot bar is determined solely by the setting of the nuts 148 at the top of sleeve 144, the presser foot is always lifted a uniform distance above the work regardless of variations in the thickness of the work.

25 To prevent injury to the presser foot and to the hereinafter described puckering mechanism in the event the machine is operated without work, means are provided for limiting the descent of the presser foot bar so that the presser foot cannot come into contact with the work support 96. Said means comprise a block 150 clamped to the presser foot bar 114 and extending into a slot 152 in the head of the machine frame, the block being so positioned on the presser foot bar that it will bottom in the slot 152 with the presser foot just clearing the surface of the work support 96. The block is also provided with a projecting pin 154 adapted to be engaged by a lever 156 the other end of which is connected by a rod 158 to a treadle, not shown, by which the presser foot may be raised by the operator to facilitate the inserting or removal of work when the machine is at rest.

removal of work when the machine is at rest.

45 The mechanism for gathering or puckering the upper is illustrated in detail in Figs 4 through 13, and is actuated by connections hereinafter described from the cam shaft of the machine to advance the upper with relation to the welt toward the needle while the latter is 50 through the work and during the time the work is clamped by the presser foot, and to hold the pucker in the upper until the work has been secured by the completion of the stitch. The puckering mechanism is mounted adjacent the 55 sewing point on a bracket 160 secured to the lower end of the presser foot bar 114 directly above the presser foot, by means of a clamp pin 162 which is tightened against the presser foot bar by nut 164, the work engaging portion of 60 the puckering mechanism receiving its work engaging and disengaging movements directly from the actuation of the presser foot bar.

65 The work engaging member of the puckering mechanism comprises a feed point 166 which is secured to the lower end of an arm 168 adjustably mounted by means of nuts 170 in the short arm 171 of the lever 172, hereinafter called the puckering lever, pivotally mounted on one arm of the bracket 160. The feed point is provided 70 with a depending spur 174 which prevents slipping of the feed point relative to the upper during the puckering operation, the nuts 170 being adjusted so that the spur partially penetrates the upper when the presser foot is clamping the upper under the pressure of the spring 116.

The portion of the upper which is advanced by the feed point during its upper puckering stroke is supported by the surface 176 on the work entering side of the work support 96. This surface is inclined to the principal work supporting surface, and forms a plane substantially parallel to the path of the feed point, so that the latter engages the upper with uniform pressure during the stroke of the feed point. The inclination of the surface 176 likewise affords a clearance space between the work support and the presser foot to accommodate the increased thickness of the puckered upper, as illustrated in Figure 5. 5 10

To insure that the welt will not be advanced 16 during the puckering of the upper and to reduce the strain on the needle during such time, the presser foot 112 is provided with a spur 178 which is oppositely faced with respect to the spur on the feed point and which engages the 20 welt adjacent the needle, as illustrated in Figs. 4 and 5, when the presser foot is in work clamping position.

The feed point 166, in addition to its function as the upper engaging portion of the puckering mechanism, is adapted to guide the welt to the sewing point, and to this end is provided with two members 180 and 182 (see Fig. 9) which cooperate to form a passage 184 through which the welt is fed diagonally downward to the sewing point, as illustrated in Fig. 4. These members are secured to the arm 168 by means of a pin 186 threaded for a portion of its length and received in a threaded hole in the arm 168. The member 182 is retained in position by a nut 188 on the threaded end of the pin 186, while the member 180 is secured by a screw 190 in the other end of the pin. 25 30 35

To accommodate welting of various widths, the spacing of the members 180 and 182 may be adjusted to vary the width of the passage 184. This is accomplished by loosening nut 188 and screw 190 and rotating the pin 186 in or out of the arm 168 to move the member 180 toward or away from the member 182. After the correct adjustment is obtained, the parts are fixed in position by tightening the nut 188 and the screw 190.

The feed point is actuated by rocking movement of the puckering lever 172, which is pivotally mounted on an arm of bracket 160 by means of a headed hollow sleeve 192. The lever 172 is rocked by connections from a bell crank lever 194, designated the rocking lever, which is pivoted on pin 196, in a rearwardly extending arm 198 of the bracket 160, and rocked continuously and with constant stroke from the cam shaft 10 of the machine.

To permit the operator readily to control the amount of puckering imparted to the upper to suit the character of the work and to suspend entirely the actuation of the feed point when securing the welt to portions of the upper which require no puckering, the means connecting the puckering lever 172 with the rocking lever 194 60 65 may be adjusted by the operator, without stopping the machine, to vary the arc of rock of the feed point, including adjustment to reduce such rocking movement to zero. The connecting means for accomplishing this result comprises 70 a pin 200 mounted in a slide 202 which is received in a guideway 204 in the long arm of the puckering lever 172, the pin engaging the slotted arm 206 of the rocking or bell crank lever 194. The slide 202 is secured to one end of a rod 208 75

which passes through an opening in the end of the sleeve 192 and is provided with a handle 210 by which the slide may be moved along the guideway to change the position of the pin 200 5 in the arm 206 with relation to the pivotal center of the bell crank lever. When the handle is pushed to the left to move the pin to the outer end of the slot in arm 206, the maximum arc 10 of rock of the feed point is obtained. As the slide is drawn to the right by handle 210, the rate of puckering is reduced, so that when the pin 200 reaches the inner end of the slot and becomes axially aligned with the pivotal center 15 of the bell crank, as illustrated in Fig. 12, the rate of puckering becomes zero, since there is then no rocking movement transmitted from the bell crank to the puckering lever 172.

The slide 202 is retained in adjusted position by means of ratchet mechanism comprising a 20 plunger 212 within the sleeve 192 and provided with a pointed end adapted to engage serrations 214 formed in the adjusting rod 208, the plunger being maintained in yielding engagement with the rod by means of a spring 216 interposed between the plunger and the closed end of the sleeve 192.

As an aid to the operator in rapidly setting the puckering mechanism to produce the desired degree of puckering during the sewing of the 30 welt and upper, the rod 208 is provided with a collar 218 secured to the rod by a thumb screw 220 and serving as an adjustable stop to limit the amount the rod may be pushed in when the puckering operation is to be commenced.

35 The bell crank lever 194 is rocked by connections from a cam disc 222 mounted on the cam shaft 10 adjacent the eccentric 118 which actuates the presser foot. The cam disc is particularly illustrated in Fig. 3, and is provided with a 40 cam path which is engaged by a follower on the end of an arm 224 mounted on the inner rock shaft 126 above referred to. An arm 226 at the other end of the rock shaft 126 is connected to the bell crank lever 194 by a link 228 the length 45 of which may be varied by means of nuts 230 whereby the clockwise limit of rotation of the bell crank may be adjusted to bring the slot in arm 206 into alignment with the pivotal center of the puckering lever 172, with the result that 50 the feed point may rock in work advancing direction up to and even into contact with the presser foot without risk of injury to the parts, since the limit of rock of the feed point is by the aforesaid adjustment rendered constant for all 55 settings of the slide 202.

Due to the fact that the link 228 is substantially perpendicular to the presser foot bar 114, the raising and lowering of the presser foot has no appreciable effect on the rocking movement 60 of the feed point, and hence the work engaging and work feeding movements are imparted to the feed point independently of, and without interference with, one another.

It has already been pointed out that the puckering stroke of the feed point takes place while the work is clamped by the presser foot and during the time the needle is through the work. To illustrate further the sequence of operations in the formation of a stitch in conjunction with 70 the puckering of the upper, reference should be made to Figures 4 to 6. Fig. 4 shows the parts just before the puckering stroke of the feed point which has been brought into engagement with the upper by the downward movement of the presser foot to work clamping position. The needle and

awl are both descending, the needle drawing the loop of thread into the work. Fig. 5 represents the parts after the feed point has moved toward the presser foot to form the pucker in the upper, and while holding the pucker preparatory to the work piercing stroke of the awl. In Fig. 5 the cam shaft has advanced substantially three quarters of a revolution from the position corresponding to Fig. 4, the needle having completed the stitch and is now at the top of its stroke and about to receive a new loop of thread. The presser foot and with it the feed point have been raised out of contact with the work, and the feed point has commenced to move toward its retracted position. After the needle has been actuated laterally to advance the upper and welt, the presser foot will descend to clamp the work and bring the feed point into engagement with the upper, the parts then appearing as shown in Fig. 4.

While the invention has been illustrated and described as embodied in a sewing machine in which the clamping and unclamping movements of the presser foot are utilized to provide work engaging and disengaging movements for the upper puckering mechanism, and in which separate actuating mechanism is provided for imparting the upper advancing movements to the puckering device, the invention is not so limited, but contemplates within its scope machines which are 30 adapted to sew a welt to an unlasted upper, having upper puckering mechanism, the work engaging and upper advancing movements of which are independently produced by separate and distinct mechanisms, or having upper puckering 35 mechanism whereby any degree of puckering from maximum to zero may be secured while the machine remains in operation.

Where, in the claims, reference is made to "means for guiding a welt and an unlasted upper 40 to the sewing point with their edges in substantial alignment" this is not to be considered as limiting the invention to a construction in which the upper and welt are guided with their edges exactly coinciding or flush, but also includes a 45 construction in which the upper and welt are presented to the sewing point with their edges more or less offset, that is, with their edges in substantially parallel alignment, but not in registration. 50

The nature and scope of the invention having thus been described, what is claimed is:

1. A machine for use in the manufacture of pre-welt shoes having, in combination, means 55 for guiding a welt and an unlasted upper to the sewing point with their edges in substantial alignment, a sewing cam shaft, and stitch forming and work feeding and clamping devices, including a hook needle, a work support engaging the upper, a presser foot cooperating therewith to engage against the welt, and means operating on the welt-engaging side of the upper to feed the upper with relation to the welt during the sewing operation to cause the upper to be secured to 65 the welt in puckered condition.

2. A machine for use in the manufacture of pre-welt shoes having, in combination, means for guiding a welt and an unlasted upper to the sewing point with their edges in substantial alignment, 70 stitch forming and work feeding devices, and a presser foot, the welt-guiding means having provision for operating on the welt, engaging side of the upper to feed the upper with relation to the welt during the sewing operation to 75

- cause the upper to be secured to the welt in pucker condition.
3. A machine for use in the manufacture of pre-welt shoes having, in combination, means for guiding a welt and an unlasted upper to the sewing point with their edges in substantial alignment, stitch forming and work feeding devices including a hook needle, a work support a presser foot movable to clamp and unclamp the work during each stitch forming cycle, and means actuated while the presser-foot is in clamped position to feed the upper with relation to the welt during the sewing operation to cause the upper to be secured to the welt in pucker condition.
4. A machine for use in the manufacture of pre-welt shoes having, in combination, means for guiding a welt and an unlasted upper to the sewing point with their edges substantially in alignment, stitch forming, work clamping, and work feeding devices including a hook needle actuated to advance the work in the line of feed, a presser foot actuated to clamp and unclamp the work during each stitch forming cycle, and means actuated while the work is clamped to feed the upper with relation to the welt to pucker the upper and hold said pucker until secured by the sewing operation.
5. A machine for use in the manufacture of pre-welt shoes having, in combination, means for guiding a welt and an unlasted upper to the sewing point with their edges substantially in alignment, stitch forming and work feeding and clamping devices including a hook needle, a work support, a presser foot actuated to clamp and unclamp the work during each stitch forming cycle, and means for feeding the upper with relation to the welt to pucker the upper while the work is clamped, said means having provision for adjustment while the machine is in operation to vary the amount of relative feeding movement imparted to the upper.
6. A machine for use in the manufacture of pre-welt shoes having, in combination, means including a welt guide for guiding a welt and an unlasted upper to the sewing point with their edges in substantial alignment, stitch forming and work feeding devices including a feed point on the welt guide adapted to engage the upper, and means for actuating the welt guide to cause the feed point to advance the upper with relation to the welt, whereby the upper may be secured to the welt in pucker condition.
7. A machine for use in the manufacture of pre-welt shoes having, in combination, means for guiding a welt and an unlasted upper to the sewing point with their edges in substantial alignment, stitch forming and work feeding devices including a hook needle and means for feeding the upper with relation to the welt, said means having provision for adjustment while the machine is in operation to vary the rate of feed of the upper with relation to the welt progressively from the maximum to zero.
8. A machine for use in the manufacture of pre-welt shoes having, in combination, means for guiding a welt and an unlasted upper to the sewing point with their edges in substantial alignment, stitch forming and work clamping devices including a pivotally mounted lever, a feed point on the lever for engaging the upper, and means for imparting four-motion feeding movements to said lever to feed the upper with relation to the welt during the sewing operation to cause the upper to be secured to the welt in pucker condition.
9. A machine for use in the manufacture of pre-welt shoes having, in combination, means for guiding a welt and an unlasted upper to the sewing point with their edges in substantial alignment, stitch forming and work feeding devices, a presser foot, and means for feeding the upper with relation to the welt while the presser foot is clamping the work to pucker the upper, the presser foot being provided with means adapted to penetrate the welt to prevent displacement of the same while the upper is being pucker.
10. A machine for use in the manufacture of pre-welt shoes having, in combination, means for guiding a welt and an unlasted upper to the sewing point with their edges in substantial alignment, stitch forming and work feeding devices, a presser foot movable to clamp and unclamp the work during each stitch forming cycle, a lever pivotally mounted adjacent said presser foot and bodily movable therewith, a feed point on the lever adapted to be moved into and out of engagement with the upper by the clamping and unclamping movements of the presser foot, and means for rocking said lever independently of the movement of the presser foot to feed the upper with relation to the welt during the sewing operation to cause the upper to be secured to the welt in pucker condition.
11. A machine for use in the manufacture of pre-welt shoes having, in combination, means for guiding a welt and an unlasted upper to the sewing point with their edges in substantial alignment, stitch forming and work feeding devices, a sewing cam shaft, a presser foot, and means for feeding the upper with relation to the welt including a lever pivotally mounted adjacent the presser foot and bodily movable therewith, a feed point on the lever for engaging the upper, a second lever adapted to be rocked from the cam shaft of the machine, and a connection joining the levers and adjustable with respect to the pivotal centers of the same to vary the arc of rock of the first lever whereby the amount of puckering imparted to the upper may be adjusted.
12. A machine for use in the manufacture of pre-welt shoes having, in combination, means for guiding a welt and an unlasted upper to the sewing point with their edges in substantial alignment, stitch forming and work feeding devices, a cam shaft, a presser foot, and means for feeding the upper with relation to the welt including a puckering lever pivotally mounted adjacent the presser foot and bodily movable therewith, a feed point on the lever for engaging the upper, a rocking lever actuated by connections from the cam shaft, means for actuating the puckering lever from the rocking lever including a pivotal connection adjustable with relation to the pivotal center of the rocking lever to vary the stroke of the puckering lever.
13. A machine for use in the manufacture of pre-welt shoes having, in combination, means for guiding a welt and an unlasted upper to the sewing point with their edges in substantial alignment, stitch forming and work feeding devices, a cam shaft, a presser foot, and means for feeding the upper with relation to the welt including a puckering lever pivotally mounted adjacent the presser foot and bodily movable therewith, a rocking lever actuated by connections from the cam shaft, means for actuating the puckering lever from the rocking lever including a pivotal connection, the position of said

pivotal connection being adjustable along the rocking lever to a point coincident with the pivotal center of the lever whereby the stroke of the puckering lever may be adjusted to zero.

- 5 14. A machine for use in the manufacture of pre-welt shoes having, in combination, means for guiding a welt and an unlasted upper to the sewing point with their edges in substantial alignment, stitch forming and work feeding devices, a work support, an upper puckering lever, a feed point on the lever, and means for actuating the lever to feed the upper with relation to the welt during the sewing operation, the work support having a portion of its surface adjacent 10 15 the feed point substantially parallel to the path of feeding movement of said feed point whereby the upper is maintained in uniform engagement

with the feed point throughout the feeding stroke of the same.

15. A machine for use in the manufacture of pre-welt shoes having, in combination, means for guiding a welt and an unlasted upper to the sewing point with their edges in substantial alignment, stitch forming, work feeding, and work clamping devices including a work support and a presser foot, and means for feeding the upper with relation to the welt while the work is 10 clamped to cause the upper to be secured to the welt in puckered condition, the work clamping devices on the work entering side being shaped to accommodate the welt and puckered portion of the upper and to support the same during a 15 portion of the sewing operation.

FRED ASHWORTH.

CERTIFICATE OF CORRECTION.

Patent No. 2,192,166.

March 5, 1940.

FRED ASHWORTH.

It is hereby certified that error appears in the printed specification of the above numbered patent requiring correction as follows: Page 4, second column, line 73-74, claim 2, for "welt, engaging" read welt-engaging; page 5, first column, line 8, claim 3, after the word "support" insert a comma; and that the said Letters Patent should be read with this correction therein that the same may conform to the record of the case in the Patent Office.

Signed and sealed this 30th day of April, A. D. 1940.

(Seal)

Henry Van Arsdale,
Acting Commissioner of Patents.
